UNITED STATES PATENT OFFICE.

CHARLES H. FIX, OF MADISON, WISCONSIN.

HAWK.

1,095,200.

Specification of Letters Patent.

Patented May 5, 1914.

Application filed July 28, 1913. Serial No. 781,586.

To all whom it may concern:

Be it known that I, CHARLES H. FIX, a citizen of the United States, and resident of Madison, in the county of Dane and State of Wisconsin, have invented certain new and useful Improvements in Hawks; and I do hereby declare that the following is a full, clear, and exact description thereof.

My invention consists in what is herein particularly set forth with reference to the accompanying drawings and pointed out in the claims of this specification, its object being to provide economical, light strong and durable plasterers' hawks having the boards thereof in detachable connection with the handles and said boards solid throughout.

Figure 1 of the drawings represents a plan view of one of my improved hawks inverted, and Fig. 2, a sectional view of the same on the plane indicated by line 2—2 in Fig. 1.

Referring by numerals to the drawings, 3 indicates the board of a plasterer's hawk the same being solid throughout and as thin as possible consistent with the requisite strength to thereby lighten the tool. The underside of the board is fashioned to present a pair of parallel ridges 4 at a predetermined distance apart, a center stud 5 and radial ridges 6 that connect the ridges 4 with the stud. Matching the ridges and studs of the board is a one piece metal frame comprising a pair of parallel preferably angle-bars 7, a center plate 8 and radial brace strips 9 connecting the plate and bars. The frame-bars are fastened, by screws 10, to the underside ridges 4 of the board, and the center plate 8 of the frame is provided with a center aperture for a bolt 11, an angular inner enlargement of the aperture serving as a recess for the engagement of a nut 12 on the bolt.

The hawk-handle 13 is counterbored for the passage of the bolt 11 through it and the plate and nut aforesaid, after which a plug 14 is set in said handle outward from the bolt-head. To separate the board from the handle, said board and frame therewith are turned in the proper direction to run the nut 12 off the bolt 11, this separation of said

board and handle being desirable so that the hawk may be packed in small compass.

The frame aforesaid is of light metal preferably aluminum and the handle-bolt is 55 preferably short, as herein shown to lighten the hawk as a whole. The board being solid throughout, it is less thick than the ordinary hawk-boards to thereby lighten said hawk that is stiffened by its underside ribbing and 60 the frame to which it is attached.

I claim:

1. A hawk comprising a board, a one piece metal frame consisting of a pair of parallel bars, a center plate and radial brace strips 65 connecting the bars and plate, means fastening the frame to the underside of the board, and a handle fastened to the center plate of the frame independent of said board.

2. A hawk comprising a board, a one piece 70 metal frame consisting of a pair of parallel bars, a center plate and radial brace strips connecting the bars and plate, means fastening the frame to the underside of the board, and a handle bolted to the center 75 plate of the frame independent of said board.

3. A hawk comprising a board having the underside thereof provided with a pair of parallel ridges at a predetermined distance apart, a center stud and radial ridges connecting those aforesaid with the stud; a one piece metal frame matching the ridges and stud of the board, means fastening the frame to the parallel ridges of said board, and a handle fastened to the frame 85 central thereof.

4. A hawk comprising a board having the underside thereof provided with a pair of parallel ridges at a predetermined distance apart, a center stud and radial ridges connecting those aforesaid with the stud; a stiffened one piece metal frame matching the ridges and studs of the board, means fastening the frame to the parallel ridges of said board, and a handle fastened to the frame 95 central thereof.

5. A hawk comprising a board having the underside thereof provided with a pair of parallel ridges at a predetermined distance apart, a center stud and radial ridges connecting those aforesaid with the stud; a one piece metal frame matching the ridges and

stud of the board, means fastening the frame to the parallel ridges of said board, a counterbored plugged handle, a bolt extending from the handle through the frame central
5 thereof, and a bolt engaging nut seated in said plate.

In testimony that I claim the foregoing I

have hereunto set my hand at Milwaukee in the county of Milwaukee and State of Wisconsin in the presence of two witnesses.

CHAS. H. FIX.
